UNITED STATES PATENT OFFICE.

CHARLES J. CALLAHAN, OF PROVIDENCE, RHODE ISLAND.

COLLAR-HOLDER.

1,377,804.

Specification of Letters Patent. Patented May 10, 1921.

Application filed February 26, 1921. Serial No. 448,081.

To all whom it may concern:

Be it known that I, CHARLES J. CALLAHAN, a citizen of the United States, residing at Providence, in the county of Providence and State of Rhode Island, have invented certain new and useful Improvements in Collar-Holders, of which the following is a specification.

This invention relates to an improved collar holder adapted for use with soft turn down collars, for engaging the opposed lateral edges of the collars to hold the same securely in position.

One object of the invention is to provide a holder so constructed as to be capable of being readily and easily attached to the collar, as well as readily removed therefrom, without liability of any part thereof catching in the collar with consequent tearing of or injury to the same.

Another object of the invention is to provide a device of this character possessing a neat and ornamental appearance, and so formed as to be capable of being properly positioned beneath the usual four-in-hand tie, or ties of that general character, and properly support the same to maintain the opposed edges of the collar and the tie in position relative to each other.

Other objects and advantages of the invention will be more fully pointed out in connection with the detailed description to follow.

Referring to the drawings:—

Figure 1 is a side elevational view of one form of my invention;

Fig. 2 is a perspective view of the same; and,

Fig. 3 is a perspective view of a slightly modified form of holder.

In the embodiment of the invention shown in Figs. 1 and 2 of the drawings, the holder is formed of a pair of curved bars 1 and 2, the curve of the bar 1 being formed with a greater radius than the curve of the bar 2, and the two bars being connected together at a point substantially midway between their ends by means of a clamp or clasp 3 folded about the two bars.

The ends of the bar 1 are turned inwardly toward the interior of the circle of which the bar is an arc to form rolls 4, preferably slightly flattened in the direction of the length of the bar, as best shown in Fig. 2 of the drawing. The ends of the bar 2 are turned outwardly from the interior of the

circle of which the bar 2 is an arc to form rolls 5, which may also be slightly flattened along lines substantially tangent to the arc 2 at the points where the rolls 5 are located. While the rolls 4 and 5 may be slightly flattened as stated in order to reduce the size of the spaces 6 between the bars adjacent to the end portions thereof this feature is entirely optional and the rolls 4 and 5 may with equal facility be made substantially circular, or may if desired be flattened in a direction at right angles to the respective bars, thereby increasing the size of the spaces 6, if such is found desirable under certain conditions of use.

The opposed rolls 4 and 5 form enlarged gripping portions, located at the ends of the said bars and co-operating with each other for engaging the opposed lateral edges of a collar to hold the same securely in position, the contacting surfaces of said rolls being curved to permit ready insertion of fabric therebetween or removal therefrom without injury to the same.

In the construction of holders formed in the manner above described, the bars 1 and 2 may be riveted or otherwise connected together before placing the clamp or clasp 3 therearound or not, as circumstances may require or the conditions of manufacture render expedient.

In the modified form of the invention shown in Fig. 3 of the drawings, 7 and 8 designate the two bars which are of similar form, the bar 7 being provided at each end with circular or slightly flattened rolls 9, while the bar 8 is provided at its opposite ends with similar rolls 10.

In this form of the invention the ends of both of the bars 7 and 8 are turned outwardly from the center of curvature of the respective bars, and the bars 7 and 8 are preferably given the same or substantially the same degree of curvature.

In the form of the invention shown in Figs. 1 and 2 of the drawings, the bars 1 and 2 are correspondingly curved with their centers of curvature located upon the same side of the completed structure, the convex surface of the bar 2 being opposed to the concave surface of the bar 1, and so arranged that the corresponding enlarged portions or rolls 4 and 5 may engage the fabric of the collar therebetween when secured thereto. In the structure illustrated in Fig. 3 of the drawings the bars are oppositely curved with

their centers of curvature located upon opposite sides of the completed structure, whereby the convex surface of the bar 7 is opposed to the convex surface of the bar 8, 5 and the corresponding inwardly positioned enlarged portions or rolls 9 and 10 formed upon opposed ends of said bars coöperate to hold the opposed edges of the collar therebetween.

10 From the above description taken in connection with the drawings it will be seen that the structure shown comprises a collar holder of novel construction, which presents a neat and ornamental appearance and is 15 capable of being easily constructed. The improved construction is also capable of being easily secured in place and readily removed without any possibility of injury to the collar, as the free ends of the bars are 20 rolled or curled under a sufficient distance to positively prevent them from engaging and tearing the fabric. It will be noted that in both of the forms of the invention illustrated herewith the parts of the holder 25 located upon opposite sides of the centrally positioned clasp are symmetrical in form, and the enlargements or rolls formed in the adjacent ends of the coöperating bars are so positioned as to engage each other thus 30 affording easy ingress or egress of the fabric to and from between the contacting surfaces of the coöperating rolls. The bars 1, 2, 7 and 8 are also preferably formed of resilient material thus facilitating the insertion 35 of the opposed edges of the collar between the ends thereof and their removal therefrom.

While I have shown the invention as embodied in the form which I regard as preferable, 40 and have described with considerable particularity the precise form of the bars and the location and shape of the enlarged portions formed at the ends thereof, it is

to be understood, that my invention is not limited to the precise form of the bars as 45 shown and described nor to the exact location and shape of the enlarged portions formed at the ends except as such structural details may be specifically included within the following claims.

50

What I claim is:—

1. A collar holder of the character described, comprising a pair of bars secured together intermediate their ends, and provided at their opposite ends with opposed 55 rolls for releasably engaging therebetween the opposed lateral edges of a collar.

2. A collar holder of the character described, comprising a pair of resilient bars curved throughout a portion of their extent 60 and provided with return bent end portions, the correspondingly located returned bent end portions normally coöperating with each other to releasably grip the edges of a collar interposed therebetween.

65

3. A collar holder of the character described, comprising a pair of correspondingly curved resilient bars provided at their opposite ends with inturned rolls for releasably engaging the opposed lateral edges of 70 a collar interposed therebetween.

4. A collar holder of the character described, comprising a pair of correspondingly curved resilient bars secured together intermediate their ends, and provided at 75 their opposite ends with inturned opposed rolls, the said rolls located at corresponding ends of the bars coöperating to releasably engage fabric interposed therebetween, the shape of said rolls being such as to permit 80 ready insertion of the fabric therebetween or removal therefrom without injury to the same.

85

In testimony whereof I have affixed my signature.

CHARLES J. CALLAHAN.
